Application July 18, 1930, Serial No. 468,919

3 Claims. (Cl. 33—93)

This invention relates to tools commonly used by carpenters in framing roofs and for analogous purposes, and consists in the provision of a combined tool embracing both a square and bevel.

The invention will be best understood from a study of the following description taken in connection with the accompanying drawings wherein:

- 10 Figure 1 is a top plan view of the device.
 Figure 2 is a side elevational view thereof.
 Figure 3 is a plan view of the dial.
 Figure 4 is a plan view of a fence block.
 Referring to the drawings by reference numerals it will be seen that the device comprises a substantially rectangular scale plate 5 of metal or other suitable material, a fence block 31 disposed against the under side of the plate 5 and of a shape shown in Figure 4 having a straight edge 31', a dial or disk member 20 arranged on the top face of the plate 5, together with a stud 29 extending downwardly through registering apertures in the dial 20 and plate 5 and having its lower end engaged in a socket 30 provided in 20 the fence block 31, said lower end of the stud being threaded into the socket 30, and the upper end of the stud being provided with a knurled head 28 that, when the stud is threaded into the socket 30, will serve to frictionally retain 25 the aforementioned parts at the desired adjustment relative to one another.

On the top face of the plate 5 and adjacent one edge thereof is a scale 6, while a scale 7 is provided on said top face adjacent the relatively 35 opposite edge, and has extending laterally therefrom at relatively opposite ends, short scales 8 and 9, the scales 6, 7, 8 and 9 being graduated in a manner common to the ordinary rule or straight edge, and are adapted to be used in measuring 40 different cuts and miters.

On said top face the plate 5 is also provided with a series of different graduations arranged in a circular manner as indicated generally at 45 10. One series of such graduations, for example, the series of graduations 16 are adapted to give the top and seat cut of octagon rafters from one to twenty-four inch rise per foot, the rise number appearing adjacent the outer edge of the circle. The graduated arc 17 is for determining the 50 cut of sheathing, hip and valley rafters. Graduations 18 are to be used for determining the top and side cuts of hip and valley rafters from one to twenty-four inches rise per foot, the rise numbers, as in the case of the graduation 16, appearing adjacent the outer edge of the circle 10.

The graduations 19 are used when determining the side cuts of octagon jack rafters, while the graduations in the arc or segment 15 are employed for determining the top and seat cuts of common rafters from one to twenty four inches rise per foot run, the rise numbers appearing adjacent the outer edge of the circle. The dial or disk member 20 on its top face has a line 21 drawn through its diameter and at one side of this line 21 is an arcuate or segmental scale 22 having inner and outer series of graduations 23 and 24, scale 22 being graduated in degrees, while at relatively spaced points in the circular scale 10 are zero indicators 11, 12, 13 and 14, adapted to be read against the graduations of the scale 22 so as to indicate to what angle the plate 5 is set in each particular case.

Also on the dial 20 there is provided on that side of the line 21 opposite to the scale 22 segmental scales 25, 26, scale 25 being graduated 75 for determining the side cuts of hip and valley rafters and scale 26 being graduated to determine the side cuts of hip and jack rafters.

The use and operation of the device will be apparent from the following illustrations.

Let it be assumed that it is desired to make, for example, a square picture frame. Manifestly the angle of the ends of the several members of the frame must be forty five degrees. In this connection the tool will be used as follows: First 80 the fence-block 31 is disposed relative to the timber with its squared edge 31' placed against one edge of the timber. Next, the disk or dial 20 is set so that the pointer 27 thereof extends at right angles to the edge 31' of the fence-block 90 31. It will thus be seen that the pointer 27 will extend transversely of the timber. The plate 5 is rotated in either direction until one of the zero indicators 11, 12, 13 or 14 are lined with the forty-five degree graduation on the scale 22 of dial 95 20. The stud 29 is then screwed down into the fence-block to hold the block 21, plate 5 and dial 20 in set position. With the parts in this position it will be apparent that the scale plate 5 will rest on the top face of the timber with two opposite edges thereof extending diagonally across the timber and then either of these said opposite edges may be used as a guide in making a mark on the timber to indicate the required cut or bevel.

Manifestly the device would be used in substantially the same manner for marking the angles for bevel cuts for octagon or common timber rafters, the cuts of jack rafters, polygons and all other such cuts.

The use of the device in obtaining the different cuts of different type rafters will be apparent from the following example; assuming that it is desired to obtain the plumb or seat cut of an 5 octagon rafter where the roof is to have a pitch of five inch rise to the foot. The squared end 31' of the fence-block will be disposed against one side edge of the rafter and the dial 20 will be set so that its pointer 27 will extend transversely 10 of the rafter and at right angles to the squared edge 31' of the fence block. The scale plate 5 will then be rotated about the stud 29 as an axis until the graduation 5 of scale 16 is in alinement with the indicator or pointer 27, when the plate 15 5 will be disposed diagonally across the rafter. The stud 29 is then screwed down to secure the parts in set position and that edge of the scale plate 5 extending diagonally across the timber will be used for guiding the marking instrument 20 in making a mark on the rafter to indicate the rafter cut.

The common rafter cuts are determined in the same manner except of course that scale 15 will be used; the hip and valley rafter cuts are determined by using the proper scale 17 and 18 while the scale 19 will be used for determining the side cuts of octagon jack. For marking the side cuts of hip and valley rafters scale 25 on the dial 20 will be used, while scale 26 on said dial will be used for marking the side cuts of hip and 30 jack rafters. However in this connection it will be noted that in using, for example, the scale 26 for determining the side cuts of hip and jack rafters a selected one of the zero pointers 11, 12, 35 13 or 14, determinable by a given pitch will be used and read against the graduations of the scale 26.

Even though I have herein shown and described the preferred embodiment of my invention, it is to be understood that the same is susceptible to changes fully comprehended by the spirit of the invention herein described, and the scope of the appended claims.

Having thus described my invention, what I 45 claim as new is:—

1. A carpenter's tool for roof framing and analogous purposes, comprising a fence-block having a squared edge adapted to be placed against one edge of a rafter, a headed stud screw threadedly engaged with the fence block, 50 a scale plate superimposed on the fence block and rotatable about the stud as an axis, a circular dial superimposed on the scale plate, said scale plate and dial being secured in adjusted 55 position between the fence block and the head of the stud when the latter is screwed home; said plate having thereon, concentric to the dial, a circular series of arcuate scales, each of which is graduated in terms of inches rise per foot

60

of common run in a pitch roof, and also having markings comprising tables of length of common run, and said dial having thereon a pointer adapted to be extended at right angles to the squared edge of the fence-block and to be read against the graduations of a selected scale for determining the angle at which the scale plate should be set for using an edge of the plate as a guide for a scribe in making a mark for the required rafter cut.

80

2. A carpenter's tool for roof framing and analogous purposes comprising a fence block having a squared edge adapted to be placed against one edge of a timber, a headed stud screw threadedly engaged with the fence block, a scale plate superimposed on the fence block, and a circular dial superimposed on the scale plate, said scale plate and dial respectively being rotatable about the stud as an axis and adapted to be secured in set rotative position between the fence block and the head of the stud when the latter is screwed home; said plate having thereon four indexes respectively arranged at the four points of the compass about the dial, and said dial having thereon an arcuate scale graduated in terms of degrees and against which a selected one of said indexes is adapted to be read for determining the angle at which the scale plate should be set for using an edge of the plate as a guide for a scribe in making a mark for the required miter cut of any desired polygon.

85

3. A carpenter's tool for roof framing and analogous purposes, comprising a fence-block having a squared edge adapted to be placed against one edge of a rafter, a headed stud screw threadedly engaged with the fence-block, a scale plate superimposed on the fence-block, and rotatable about the stud as an axis, a circular disk superimposed on the scale plate and having a centrally located aperture through which the stud extends, said scale plate and dial being adapted to be clamped at the desired rotative adjustment between the fence-block and the head of the stud when the latter is screwed home; said plate having thereon four indexes respectively fixed at the four points of the compass about the dial, and said dial having thereon arcuate scales, each of which is graduated in terms of inches rise per foot of common run in a pitch roof, and each scale being adapted to be read against a selected one of the indexes determinable by a given pitch for determining the angle at which the scale plate should be set for using an edge of the plate as a guide for a scribe in making a mark for the required rafter cut.
